BRAKE BEAM SUPPORT

Donald S. Barrows, Rochester, N. Y., assignor to
The Symington-Gould Corporation, Depew,
N. Y., a corporation of Maryland

Application January 15, 1945, Serial No. 572,892

30 Claims. (Cl. 188—190)

1

This invention pertains to a brake beam support for a railway car truck and more particularly to a compensating type thereof.

A particular and broad object of the invention is the provision of an adjusting or compensating means so associated with a side frame and journal box that, irrespective of the vertical travel of a side frame relative to a journal box, a brake beam will be maintained in a definite and fixed position.

A feature of the invention is the provision of rigid means pivotally secured to a side frame so as to be carried vertically with the side frame and having spaced portions respectively and flexibly secured to a journal box and a brake beam support or guide.

An added feature of the invention is the provision of a vertically directed member positioned inwardly of a truck with vertically spaced means pivotally connecting the member to a side frame and being responsive to a vertical action between a side frame and journal box.

The above objects and features, as well as numerous others, will become apparent from the succeeding description considered together with the accompanying drawings, wherein:

Figure 1 is a side elevational view of a portion of a railway truck embodying the present invention.

Figure 2 is a plan view of the structure illustrated in Figure 1.

Figure 3 is a vertical sectional view taken along the lines 3—3 of Figure 2, looking in the direction of the arrows.

Figure 4 is a vertical sectional view taken along the lines 4—4 of Figure 1, looking in the direction of the arrows.

Figure 5 is a vertical sectional view taken along the lines 5—5 of Figure 2, looking in the direction of the arrows.

Figure 6 is a horizontal sectional view taken along the lines 6—6 of Figure 1 and looking in the direction of the arrows.

Figure 7 is a side elevational view of another specie of the invention.

Figure 8 is a plan view of the structure illustrated in Figure 7.

Figure 9 is a vertical sectional view taken along the lines 9—9 of Figure 8 and looking in the direction of the arrows.

Referring now in detail to the drawings, wherein, throughout the several views, like reference characters indicate like parts, the structure of Figures 1 through 6 illustrating one specie of the invention will be considered initially. The railway car truck, indicated generally by the reference character 1, comprises a pair of transversely spaced, longitudinally extending side frames, only a portion 2 of one of which is illustrated because it is commonly known that a rail-

2

way car truck is formed as above described. The side frames are tied together or connected intermediate their ends by a load carrying member or transversely extending bolster 3 having an end portion 4 extending into a window opening 5 of each side frame to be there interlocked as desired to the side frame and to transmit the load of the car body (not shown) to the side frames. The railway car truck with which the present invention is particularly adaptable is a type thereof wherein the side frame is resiliently supported and, accordingly, the vertical disposition of the side frame is most usually continually changing in running service and also during the loading and unloading of the car body. As illustrative of the type of railway car truck hereinabove discussed, there is shown a journal box 6 forming a housing for bearings of any type (not shown) and which are operatively associated with a wheel and axle assembly 7. The journal box, disposed between jaws 8 of the side frame adjacent an extremity thereof, may have outstanding therefrom wings or shelves 9 with the jaws forming containers for resilient means 9b, the latter of which are interposed between the side frame and journal box shelves to thereby present a flexible or resilient support for the side frame. This structure of journal box mounting may be as illustrated, described and claimed in United States Patent No. 2,297,863 granted October 6, 1942, to D. S. Barrows et al. In such a railway car truck, because of the presence of the flexible or resilient support, and considered together with the fact that the vertical disposition of the axis of the wheel and axle assembly is, throughout all service truck movements, constant with respect to a supporting rail, the vertical relationship between the side frame and wheel and axle assembly is subject to variation.

Generally, the means employed to impede the progress of a railway car or retain a railway car in a predetermined position, is a component of a railway car truck commonly called a brake beam and designated in the several views of the drawing by the reference character 10. The brake beam extends horizontally or transversely of the truck and has associated with extremities thereof brake shoe heads 11 which carry replaceable brake shoes 11a arranged to contact the wheels of a wheel and axle assembly.

For reasons which are apparent to those skilled in the art and need not be herein enumerated, an ideal condition is attained when the brake beam, though supported by a part of the railway truck, is maintained at a predetermined elevation so that, irrespective of any vertical variation between the side frame and wheel and axle assembly, the brake beam will at all times travel along a fixed and definite path during the application or release action of the brakes. Toward

the attainment of the above there is provided a brake beam carrier or support 12 desirably of cast form but, as will be apparent, may be made equally as well as a fabricated component. The instant species is primarily concerned with the type of brake beam having an extension 13 of elongated cross sectional configuration which projects outwardly of the truck from a related brake head in contrast to the type employing a pivotal or swing hanger interlocked with the 10 brake head. Accordingly, the brake beam support has, at a lower extremity thereof, a guideway 14 formed by top and bottom walls 15 and 16, respectively, spaced one above the other and both being joined near or at their wheel adjacent extremities by an end connecting wall 17. The guideway is further defined by a side wall 18 joining the previously mentioned walls so that the guideway opens inwardly of the truck both 15 toward the longitudinal and transverse center lines thereof. Accordingly, the inside of the guideway is open for accommodation of the brake beam extension 13, and what might be termed the rear side of the guideway is open so that the brake beam may be introduced into the guideway through this latter mentioned opening. Carried by the top and bottom walls are bearing 20 or wear plates 19 secured to the related walls by any desired means. As previously indicated, the extension 13 of the brake beam projects into the guideway and is retained in this position by the related walls and the wear plates associated with the top and bottom walls. From long 25 and established practice, brake beams are most usually disposed below a horizontal plane bisecting the axis of the wheel and axle assembly, and are arranged so as to move along a path which, if extended, bisects the axis of the wheel and axle assembly so that the included angle between the extended path and horizontal plane above mentioned will approximate 12 degrees. Accordingly, the guideway is inclined or disposed upwardly and outwardly or longitudinally of the truck so that the brake beam will travel, during application and release of the brakes, along a path which, if projected, would intersect the 30 axis of the wheel and axle assembly and present with a horizontal plane, an included angle approximating 12 degrees.

As previously implied, means has been incorporated in the truck to maintain the guideway in a fixed position and, as exemplary of such a means, there is provided a bracket, depending means or stationary hanger 20 formed by a plane web 21 integral with and extending downwardly of the truck from a tension member 22 of the side frame and intermediate the bolster opening 5 and journal box accommodating jaws. The plane web, disposed desirably along an outer edge of the tension member, has its free or lower end terminating in an apertured hub or bearing member 23, the axis of which is substantially horizontal and arranged at an angle to a vertical plane extending longitudinally of the side frame. In order to reinforce the bracket against stresses to which it will be subjected in service, an inner rib 24 is formed integrally with the web to extend therefrom inwardly of the truck and have its respective ends merge with the tension member and hub. For a like reason, parallel outer ribs 25 outstand from the bracket web to extend between the tension member and bearing. Positioned toward an associated end of the side frame from the previously described bracket is an auxiliary bracket, depending means or stationary 35

hanger 26 formed in part by a vertical wall 27 integral with a jaw 8 of the side frame between the journal box and bolster. This vertical wall is, in fact, a downward continuation of a part of the related jaw on the outer side of the side frame so as to not interfere with any of the truck main components. The vertical wall also terminates in a hub or bearing 28 which has an axis in substantial perfect alignment with the axis of the bearing 23. Because of the short effective length of the vertical wall, it is believed only necessary to reinforce it against service stresses by a single stiffening rib 27a outstanding from the vertical wall as an integral part thereof and joining the related jaw and bearing 28. Extending through and connecting the aligned bearings is a pivotal bar, pin or shafts 29 which may or may not be arranged to rotate about its axis relative to the supporting bearings. The shaft has extremities 30 projecting beyond the bearings to thereby present cylindrical, outstanding horizontal axles.

Carried by the shaft axles is an integral, firm, rigid means or crank 31 desirably substantially U-shaped in plan and comprising an intermediate shank or bar 32 which extends horizontally for at least the distance over the spaced bearing and is of semi-circular or arcuate configuration in cross section with the inside radius thereof slightly greater than the outside radius of the bearing. By reason of this shank configuration the crank is easily or readily associated or assembled with the hangers and is free to rotate within certain limits about the axis of the shaft axles. Associated with each end of the shank is an annulus or washer type end wall 33 forming in effect a barrier or end closing of the shank. The end walls telescope or overlie the bearings to be disposed in the close proximity thereto and are provided with suitable apertures 35 which accommodate rather neatly the shaft axles so that while the rigid means or crank is arranged to rotate about the axis of the shaft it is also prevented from shifting in a direction axially of the shaft. Cotters or any removable means 34 are associated with the free ends of the shaft axles to prevent an unwarranted or accidental displacement of the shaft.

Extending inwardly of the truck from the annulus adjacent the jaw hanger is a stiff, firm arm 35 desirably of U or channel shape in vertical cross section and projecting toward the area beneath the related journal box where it terminates in an angularly directed pin or journal 36. The axis of the journal is also disposed horizontally and at an angle to the vertical longitudinal plane of the side frame hereinabove referred to so that the axis of the journal is parallel to or substantially so but spaced from the axis of the rotary bar or shaft for reasons which will be hereinafter made apparent. Because the side frame moves vertically relative to the substantially stationary journal box and also because of the slight tolerances between juxtaposed guiding surfaces of the journal box and side frame which allow a slight transverse movement between the journal box and side frame, it is believed at the present writing that the juncture of the arm and journal box should be made flexible. While it might be quite feasible to permit the journal of the arm to ride in a groove beneath the journal box it is, however, preferred that the journal extend through a round or cylindrical bushing 37 which is embedded in a block 38 of relatively resilient material such as rubber, rubber compound or the like. The resilient block has upper and lower

wearing or rubbing plates 39 securely bonded thereto. So as to maintain the block and hence the arm journal in a somewhat fixed and predetermined position, a strap or U-shaped bracket 40 is formed preferably integral with the bottom of the journal box, and thus the block and wearing plates are arranged in the vertical space between the journal box bottom and strap. The free end of the journal is provided with a transverse slot into which is threaded a clip 41 retaining a washer 42 in position against the block thereby locking the block to the arm journal. Because of the relative compound action between the journal box and side frame, as well as the fact that the position of the shaft is fixed with respect to the side frame, the strap is somewhat elongated in order that the block and encased journal may, in service, move in a direction substantially transversely of the truck. It may be well to here mention that preferably the vertical center of the block coincides normally with the vertical center of the journal box as illustrated by the intersecting diagrammatic lines in Figure 2. By this alignment of vertical centers it is believed that a true and accurate vertical movement between the journal box and side frame will be reflected in the integral or rigid means or crank. It will, of course, be appreciated that the vertical centers above mentioned need not be in alignment and no such limitation is to be read into this description as it is not implied or intended because a reflection of the journal box-side frame movement may be equally effective by the arm or arm journal being associated with any part of the journal box.

Extending inwardly of the truck from the other annulus is a firm, rigid arm 43 which may be classified as the guide arm as opposed to the previously discussed arm, the latter of which also for the sake of convenience and identification, may be termed as the journal box arm. The guide arm, also of channel cross section, projects beneath the side frame through the plane thereof to terminate in a boss or embossment 44 having an aperture in axial alignment with the journal box arm journal. Depending from the bottom wall of the brake beam support is a pair of spaced lugs or ears 45 arranged in straddling or overlapping relation with the guide arm boss and correspondingly apertured to accommodate a hinge pin 46 pivotally connecting the guide arm and brake beam support. The brake beam support is thus carried in a fixed, definite or predetermined position and because the effective lengths of the journal box arm 35 and guide arm 43 are equal, a vertical movement of the side frame relative to the journal box will result in the pivotal bar 29 being carried vertically through a corresponding distance. As previously stated, the journal box or the wheel and axle assembly remains at a fixed elevation and when the side frame moves vertically, the rigid means or crank 31 will pivot about the pivotal bar but the brake beam support 12 will, like the journal box, remain at a fixed elevation to permit the brake beam to travel along its fixed, predetermined path toward or away from the axis of the wheel and axle assembly.

Because of the pivotal connection between the guide arm and brake beam support it is believed advisable to steady the brake beam support with an additional connection and, accordingly, a column 47 of the side frame is provided with an inwardly directed bearing 48 while spaced horizontally therefrom is an outwardly directed bear-

ing 49 outstanding from the side frame at the juncture of the tension member and compression member 50. The axes of these upper or two latter mentioned bearings are in horizontal alignment and desirably in vertical alignment and parallel to but spaced above the axis of the pivotal bar so as to be angular to the vertical longitudinal plane of the side frame. The space between the upper bearings is a part of a side opening 51 in the side frame which is bounded by the compression member, the tension member and the column. Threaded through the upper bearings and bridging the space therebetween is a pivot rod 52 locked in operable position by the presence of cotter pins or keys 53 associated with the respective ends of the pivot rod outwardly of the bearings. Sleeved over the pivot rod between the upper bearings is a link 54 comprising spaced sockets 55 joined by an intermediate spacer 56, the latter of which is also of circular cross section or of substantially semi-cylindrical formation to be spaced from the pivot rod. The sockets and intermediate spacer have, extending therefrom, inwardly of the truck through the side frame side opening, a leg 57 with peripheral, angularly disposed, side stiffening flanges 57a to terminate in an apertured cylindrical extremity 58. The effective length of the link is equal to the effective length of the guide arm and, accordingly, the axis of the cylindrical extremity is parallel to the axis of the pin 46 and desirably spaced directly thereabove.

The top wall 15 of the guideway has, upstanding vertically therefrom, a pair of spaced standards, stanchions or posts 59 which extend upwardly from the top wall to embrace the cylindrical link extremity therebetween. Apertures are provided in the posts at their upper limits with the apertures being disposed in axial alignment with the cylindrical extremity of the link to accommodate a pivot pin 60 removably securing the link to the guide posts. Accordingly, when the side frame moves vertically relative to a journal box, the pivot bar 52 and shaft 29 will be carried through the same distance and, because of the particular equal lengths and disposition of the link 54 and guide arm 43, the guide means 12 will be held in a predetermined, fixed or illustrated position. If desired, a gusset 61 may be provided at the juncture of one of the posts and guideway top wall and a connecting plate 62 may be formed integrally with the posts immediately below their connection to the link.

Referring now in detail to the second species of the invention illustrated in Figures 7, 8 and 9, there is disclosed a portion of a railway car truck 1a including a pair of side frames, only a portion 2a of one being shown. Connecting the side frames intermediate their ends is a bolster element 3a having an end portion 4a interlocked with a side frame to form a connection between the two transversely spaced side frames. In like manner, each side frame under immediate consideration is supported at each end thereof by a journal box 6a with resilient means (not shown) disposed between the side frame and journal box. The present truck has associated therewith a brake beam 9a having an extension 13a and adapted to move toward and away from a wheel of a wheel and axle assembly 1a. Carrying the brake beam is a brake beam support 12a positioned inwardly of the truck and comprising a bottom wall 16a underlying and functioning as 75 a bearing for the brake beam extremity. The

bottom wall is inclined so that the center line of a guideway 14a, partially defined by the bottom wall, intersects the axis of the wheel and axle assembly so that the included angle between the extended center line and a horizontal plane bisecting the axis of the wheel and axle assembly will, as in the previous case, approximate 12 degrees. Closing the outer side of the guideway is a vertical side wall 18a upstanding vertically from the outer edge of the bottom wall and merging into a somewhat narrow top wall 15a which is parallel with the bottom wall but spaced a predetermined distance above the latter. The narrow top wall, side wall and bottom wall are all joined integrally adjacent a common extremity by an end wall 17a which closes one end of the guideway. In the instant structure, for reasons which will be later explained, the narrow top wall extends across only a portion of the upper limits of the guideway where it merges into an upstanding barrier or vertical web 63 which extends, along its length, for substantially the full length of the narrow top wall. Projecting inwardly of the truck from the upper extremity of the barrier is an overhanging lip 64 which may, if desired, be made as illustrated and thus, coextensive with the barrier. Disposed within the offset formed by the vertical web and lip is a leg 65 of a shelf 66 with the leg being removably attached to the vertical web through the medium of any means such as the illustrated rivets 67. Another leg 68 of the shelf is angularly disposed to the first named leg and forms, in effect, a continuation of the narrow top wall to be substantially coextensive therewith and complete the top wall so that the upper limits of the guideway are thus defined to guide or direct a brake beam toward or away from a wheel. Wear compensating means is associated with the guideway as exemplified by the wear or bearing plate 19a which is of sinuous formation in cross section and comprises a base plate 69 having a clip-like edge 70 curling about the free edge of the lower wall. The other edge of the base plate merges into a vertical flange 71 which lies against the side wall and turns into a re-entrant flange 72. Upstanding from the re-entrant flange is a nib or short finger or fin 73 extending into an accommodating relief and bound between the narrow top wall and shelf to retain the bearing or wear means or plate in operable position.

Depending from and integral with the side frame are brackets, depending means or hanger elements 29a and 28a spaced a predetermined distance apart and carrying at or adjacent their lower extremities hubs or bearings 23a and 28a respectively. The hubs, which have their axes in alignment and disposed at an angle to a vertical, longitudinal plane of the side frame, accommodate a pivotal bar or shaft 29a with the latter carrying, through its cylindrical extremities 30a, an integral, rigid means or crank 31a. The present crank is identical with the previously mentioned crank 31 and, accordingly, has a journal box arm 35a underlying, interlocked with and actuated by a journal box 6a through the medium of a flexible connection 33a and a journal box clip 40a. In like manner, a guide arm 43a extends from the other end of the rigid means shank 32a to be interlocked through the medium of a pin 46a to spaced lugs or ears 45a which depend from the guideway bottom wall. As in the previously discussed structure, the instant specie is provided with bearings 48a and 49a to

carry an angularly disposed pivot rod 52a while a link 54a connects the pivot rod and upper extremities of stanchions or posts 59a upstanding vertically from the brake beam support vertical web.

A further distinction between the two illustrated species of the present invention resides in the alteration in design of the brake beam support. In this regard it is deemed advisable to here state that in lieu of guiding the brake beam extremities along a fixed path, through the medium of the guideway, it may be desired to suspend the beam from a swing hanger illustrated diagrammatically in all of the figures showing the second specie and designated by the reference character 74. For reasons that are obvious to those skilled in the art, an operator may require either a guideway or a swing hanger for the support of a brake beam and, with this thought in mind, the brake beam support includes a vertical plate-like rib 75 formed integrally with one or the bolster adjacent post of the pair of posts 59a. The rib extends upwardly from a portion of the lip 64 to terminate horizontally away from the posts in a normally disposed end flange 76, the latter of which is carried down over and formed integrally with the barrier 63, narrow top wall and side wall. At or near the upper limits of the end flange a jaw 77 is formed to open away from the bolster and be spaced inwardly of the truck from the plate-like rib. The jaw, desirably in longitudinal alignment with the wheel of the wheel and axle assembly, comprises transverse extensions 78 of an upper portion of the end flange and upwardly vertically spaced fingers or ledges 79 which, near their free ends, are apertured to accommodate any type of removable retaining means such as a pin (not shown). The swing hanger, if required in lieu of the guideway, is associated with the jaw to be interlocked therewith and functions as an optional movable support for the brake beam. When the swing hanger is employed, the shelf 66 as well as the bearing plate 19a is omitted from the structure, because the former interferes with the successful operation of the swing hanger and the latter is not required. It is to be noted, however, that irrespective of the medium employed for supporting the brake beam, namely the guideway or swing hanger, the remaining components will function as hereinabove described and thus act as a compensating means for maintaining the brake beam in a substantially fixed, elevated position relative to an associated wheel of a wheel and axle assembly.

From the above it will be noted that various changes and alterations may be made to the illustrated and described constructions without departing from within the spirit of the invention and scope of the appended claims.

I claim:

1. In a brake beam compensator for a railway car truck including a journal box supporting a vertically movable side frame, the combination of, spaced bearings depending from said side frame, a brake beam carrier spaced inwardly of said side frame from said bearings, and rotatable means carried by said bearings; said rotatable means supporting said brake beam carrier and being movably connected to said journal box.

2. In a brake beam compensator for a railway car truck including a journal box supporting a vertically movable side frame, the combination of, means depending from said side frame, a brake beam carrier spaced inwardly of said de-

pending means, and rigid means carried by said

depending means and connecting said journal box and brake beam carrier so that, irrespective of the vertical relationship of the side frame and journal box, said brake beam carrier will remain constant vertically relative to said journal box.

3. In a brake beam compensator for a railway car truck including a journal box supporting a vertically movable side frame, the combination of, means firmly secured to said side frame, a brake beam guide spaced inwardly of said truck from said side frame, and rigid means movably associated with said first named means and connected to said journal box and brake beam guide.

4. In a brake beam compensator for a railway car truck including a journal box supporting a vertically movable side frame, the combination of, hanger means carried by said side frame, a brake beam guide spaced from said hanger means inwardly of said truck, and rigid means rotatably associated with said hanger means and underlying said journal box and brake beam guide.

5. In a brake beam compensator for a railway car truck including a journal box supporting a vertically movable side frame, the combination of, hanger means carried by said side frame, a brake beam guide spaced from said hanger means inwardly of said truck, and rigid means rotatably associated with said hanger means and having spaced portions underlying said journal box and said brake beam guide respectively.

6. In a brake beam compensator for a railway car truck including a journal box supporting a vertically movable side frame, the combination of, means rigid with said side frame, a brake beam support spaced inwardly of said truck from said first named means, and rigid means pivotally connected to said first named means; said last named rigid means having spaced portions underlying said journal box and brake beam support.

7. In a brake beam compensator for a railway car truck including a journal box supporting a vertically movable side frame, the combination of, means rigid with said side frame; a brake beam support spaced inwardly of said truck from said side frame, rigid means pivotally connected to said first named means, said last named rigid means having spaced portions underlying said journal box and brake beam support, and means spaced from said last named rigid means and being pivotally associated with said side frame and brake beam support.

8. In a brake beam compensator for a railway car truck including a journal box supporting a vertically movable side frame, the combination of, means rigid with said side frame, a brake beam support spaced inwardly of said truck from said side frame, and rigid means pivotally connected to said first named means; said last named rigid means having spaced portions movably secured to said journal box and brake beam support.

9. In a brake beam compensator for a railway car truck including a journal box supporting a vertically movable side frame, the combination of, means rigid with said side frame, a brake beam support spaced inwardly of said truck from said side frame, rigid means pivotally connected to said first named means, and spaced means outstanding from said rigid means; said spaced means being movably secured to said journal box and brake beam support.

10. In a brake beam compensator for a railway car truck including a journal box supporting a vertically movable side frame, the combination of,

means rigid with said side frame, a brake beam support spaced inwardly of said truck from said side frame, rigid means pivotally connected to said first named means; and spaced means outstanding from said rigid means; one of said spaced means underlying said journal box and another of said spaced means underlying said brake beam support.

11. In a brake beam compensator for a railway car truck including a journal box supporting a vertically movable side frame, the combination of, means rigid with said side frame, a brake beam support spaced inwardly of said truck from said side frame, rigid means pivotally connected to said first named means, and spaced means outstanding from said rigid means; one of said spaced means being resiliently connected to said journal box and another of said spaced means being pivotally connected to said brake beam support.

12. In a brake beam compensator for a railway car truck including a journal box supporting a vertically movable side frame, the combination of, means rigid with said side frame, a brake beam support comprising for selective or alternative use, a guideway and brake hanger jaw spaced inwardly of said truck from said side frame, and rigid means extending between said journal box and brake beam support; said rigid means being pivotally secured to said first named means.

13. In a brake beam compensator for a railway car truck including a journal box supporting a vertically movable side frame, the combination of, means rigid with said side frame, a brake beam support comprising for selective or alternative use, a guideway and brake hanger jaw in vertical spaced relation to said guideway, said brake beam support being spaced inwardly of said truck from said side frame, rigid means extending between said journal box and brake beam support; said last named rigid means being pivotally secured to said first named means, and spaced movable means extending between said brake beam support and side frame.

14. In a brake beam compensator for a railway car truck including a journal box supporting a vertically movable side frame, the combination of, means rigid with said side frame, a brake hanger bracket spaced inwardly of said truck from said side frame, and rigid means pivotally connected to said first named means; said last named rigid means having spaced portions of substantially equal effective lengths and movably connected to said journal box and brake hanger bracket.

15. In a brake beam compensator for a railway car truck including a journal box supporting a vertically movable side frame, the combination of, spaced means on said side frame, a brake beam support spaced inwardly from said side frame, and rigid means pivotally connected to said spaced means; said rigid means having spaced portions of substantially equal length and extending inwardly from said side frame to be flexibly connected to said journal box and brake beam support respectively.

16. In a brake beam compensator for a railway car truck including a journal box supporting a vertically movable side frame, the combination of, spaced means on said side frame, a brake beam support spaced inwardly from said side frame, and rigid means pivotally connected to said spaced means; said rigid means having spaced portions extending inwardly of said truck from said side frame to be flexibly connected to said

11

journal box and pivotally connected to said brake beam support respectively.

17. In a brake beam compensator for a railway car truck including a journal box supporting a vertically movable side frame, the combination of, spaced means on said side frame, a brake beam support spaced from said side frame, and horizontal rigid means pivotally connected to said spaced means and angularly disposed relative to said side frame; said rigid means having spaced portions of substantially equal length and extending inwardly of said truck from said side frame to be flexibly secured to said journal box and movably secured to said brake beam support respectively.

18. In a brake beam compensator for a railway car truck including a journal box supporting a vertically movable side frame, the combination of, a brake beam support spaced from said side frame, and rigid means pivotally secured to said side frame so as to move vertically therewith; said rigid means having spaced portions movably secured to said journal box and brake beam support.

19. In a brake beam support, the combination of, a guideway arranged to carry a load of and direct a brake beam, and attaching elements projecting upwardly and downwardly from said guideway forming vertically spaced supports for said guideway and pivotal connections to a side frame.

20. In a railway car truck wherein a frame is arranged to move vertically relative to a vertically stationary journal box, the combination of, a member comprising a guideway spaced from said frame, and pivot means carried by said frame; said pivot means connecting said member and journal box and being arranged to maintain said member in a substantially fixed vertical position relative to said journal box during said vertical frame movement.

21. In a brake beam compensator for a railway car truck including a journal box supporting a vertically movable side frame, the combination of, spaced means on said side frame, a vertically extending means spaced from said side frame, brake beam guide means adjacent a lower extremity of said vertical extending means, rigid means pivotally secured to said spaced means and having spaced portions extending inwardly of said truck to be flexibly connected to said journal box and vertically extending means respectively, and link means pivotally connected to said vertically extending means adjacent an upper extremity thereof and to said side frame.

22. In a brake beam compensator for a railway car truck including a journal box supporting a vertically movable side frame, the combination of, a brake beam support spaced from said side frame, pivot means carried by said side frame so as to move vertically therewith, and rigid means carried by said pivot means and having portions flexibly secured to said journal box and brake beam support respectively.

23. In a brake beam support, the combination of, a guideway and attaching elements formed integrally with said guideway presenting vertically spaced hinging means by which said guideway is supported in a fixed position.

24. In a brake beam support, the combination of, a lower guideway, attaching elements projecting in opposite directions from said guideway for pivotal support of said guideway and con-

12

nexion to a side frame, and a brake hanger jaw spaced above said guideway.

25. In a brake beam support, the combination of, a guideway inclined with respect to a horizontal plane for slidably supporting a brake beam, vertically directed attachments projecting above and below said guideway for affording pivotal support of said guideway from a side frame.

10 26. In an integral brake beam support, the combination of, a guideway inclined with respect to a horizontal plane, vertically directed attachments extending in opposite directions from said guideway for affording vertically spaced pivotal connections to a side frame, and a brake hanger jaw disposed above said guideway.

15 27. In a side frame arranged for vertical movement relative to a journal box, the combination of, a tension member, a jaw at the end of said tension member for the accommodation of said journal box, a brake rigging hanger supported by and depending below said jaw, and a second brake rigging hanger supported by said tension member; said hangers being spaced horizontally from one another.

20 28. In a side frame arranged for vertical movement relative to a journal box, the combination of, a tension member, a jaw at an end of said tension member for the accommodation of said journal box, a brake rigging hanger supported by said jaw, a second brake rigging hanger supported by said tension member, and said hangers being spaced horizontally from one another; both of said hangers terminating in hubs for the accommodation of pivot means.

25 29. In a crank for use in a brake rigging and with a journal box, the combination of, an intermediate shank, an annulus formed at each end of said shank, an arm extending horizontally from one annulus and terminating in means arranged to underlie said journal box, and a second arm extending horizontally from the other annulus and terminating in means attachable to a brake beam support.

30 30. In a rigid crank for use in a brake rigging and with a journal box, the combination of, an intermediate shank of semi-circular cross-section, a hub formed at each end of said shank, an arm of angular-shaped cross section extending horizontally from one of said hubs and terminating in angularly disposed means arranged to underlie said journal box, and a second arm of angular-shaped cross section extending horizontally from the other of said hubs and terminating in an attachment for a brake beam support.

DONALD S. BARROWS.
